OIL BURNER

William Edward Taft, Athol, Mass., assignor to
 Taft Oil Burner Company, Athol, Mass., a
 corporation of Massachusetts

Application May 31, 1930. Serial No. 457,855

2 Claims. (Cl. 158—87)

This invention relates to liquid fuel burners of the type wherein liquid fuel is vaporized in an open top channel or trough and burns in the space between perforated combustion tubes or 5 chimneys that surround the channel opening and extend upwardly thereabove.

This invention is essentially an improvement upon the construction described and claimed in my application Serial No. 457,854, filed May 31, 10, 1930, now Patent No. 1,901,271.

The present invention has for one of its objects the provision of improved means for distributing the liquid oil from a single oil passage into a plurality of spaced locations in the vaporizing channel.

A further object of the invention is the provision of a burner base having an annular vaporizing channel provided with walls defining a plurality of angularly spaced and independent 20 air passages which are located around a central fuel passage and constitute the walls thereof and also constitute the walls of a plurality of oil passages which are located between the air passages and provide communication between the 25 central oil passage to spaced locations of the channel.

A yet further object is generally to improve the construction and operation of liquid fuel burners of the type above set forth.

30 Fig. 1 is a plan view of a burner base embodying the present invention.

Fig. 2 is a sectional elevation taken along line 2—2 of Fig. 1.

35 Fig. 3 is a section taken along line 3—3 of Fig. 1.

The burner here shown as embodying the present invention comprises a base 10 having an inner ring 12 and an outer ring 14, both rings being concentric and spaced apart to provide between them an annular air passage 16 which is open at the top and the bottom of the base. The outer ring 14 has upstanding outer and inner walls 18 and 20, respectively, and a bottom wall 22, which walls define between them an annular 40 endless vapor channel 24 which is open at the top. The inner ring 12 is provided with an outer annular upstanding wall 26 and a plurality of angularly spaced arcuate inner walls 28 struck from a common radius. A horizontal bottom wall 22, which walls define between them an annular endless vapor channel 24 which is open at the top and which is of large radial width as compared with the narrow radial width of the vapor channel 24. 50 The arcuate walls 28 cooperate with integrally-

connected radially inwardly directed walls 34 and inner arcuate walls 36 to define a plurality of segmental air passages 38 which are located within the vaporizing channel 32 and are open at the top and the bottom of the burner base. The inner arcuate walls 36 define a central annular opening 40 into which liquid fuel is adapted to flow through the vertical central opening passage 42 that communicates with the bottom of said passage 40 through the depending boss 44. A liquid fuel pipe 46 is fitted into the lower end of said passage 42 and communicates with a suitable source of liquid fuel supply, not shown, and which is adapted to maintain a level of liquid in the burner base that is slightly above the bottom wall thereof and below the tops of the upstanding walls. The radial walls 34 of adjacent air passages 38 are spaced apart to provide open top radial passages or pockets 48 which are offset from the vaporizing channel 32 and extend radially inwardly therefrom and communicate with the central fuel passage 40 so that fuel can flow from said central passage into said vaporizing channel at a plurality of spaced locations therein. As here shown four such channels 48 are provided which are located 90° apart. Relatively thin projections 50 upstand from the bottom walls 30 of the vaporizing channel in front of said passages 48 and are adapted to locate igniting wicks, not shown, within said channel in such installations that render such wicks 55 admissible.

When the burner is in steady operation the liquid fuel is adapted to be vaporized entirely in the vaporizing channel 32 and mainly in the passages 48 thereof. Means are provided to conduct the fuel vapor into the outer vapor channel 24. Said means includes a plurality of ribs 52 which connect said rings 12 and 14 and extend across the annular air passage 16 therebetween. Said ribs are provided with ducts 54 which open into both channels so that vapor from the inner channel can flow into the outer channel. The ribs 52 are staggered with respect to the passages 48 so that a uniform distribution of vapor in the two channels is assured. A cap 56 is seated upon the walls of the air passages 38 and has a radially outwardly extended portion 58 that overlies a portion of the open top of the vaporizing channel and confronts and is terminated in spaced relation with the outer wall 26 thereof whereby to provide an annular opening 60 for said vaporizing channel that is of reduced radial extent. Said cap is provided with openings or passages 62 therein which are in register with the passages 38 so as to per-

mit air to flow upwardly through the passages 38 into the interior of the burner. The cap overlies and constitutes a closure for the open top passages 48 and also for the central passage 40. The 5 cap is provided with an upstanding boss 64 in the middle and radially outwardly extended ribs 66 which are located between the openings 62. One of said arcuate walls 28 is provided with a projection 68 the upper end of which is seated in a 10 notch 70 in the under face of the cap whereby to secure the cap on the base against rotation and thereby to lock the cap with the openings 62 therein in register with the passages 38. A perforated combustion tube 72 is seated upon the cap 15 at the outer periphery thereof and surrounds the inside of the opening 60 of the vaporizing channel and upstands thereabove. A similar perforated tube 74 is seated upon the wall 26 and upstands thereabove. The two perforated tubes 20 are located in spaced concentric relation and define between them a combustion chamber 76 in which the vapor rising through the opening 60 is burned. The walls 18 and 20 of the outer or vapor channel 24 also support similar concentric spaced tubes 78 and 80 which define between them a combustion chamber 82 in which the vapor rising through the open top of said channel 24 is burned. A cover 84 is seated upon the open 25 top of the tube 72 and thus constitutes a closure for the top of said tube and thus constrains the air that passes through the passages 38 of the burner to flow through the perforations of said tube and burn with the vapor in the combustion chamber 76. A screw 86 passes through said 30 cover 84 and is fastened in the boss 64 of the cap 56 whereby to unite the cover, the cap, and the tube 72 as a unit so that they can be removed from the burner base for inspection and cleaning 35 of the vaporizing channel when necessary. An annular ring 88 is seated upon the combustion 40 tubes 74 and 78 and thereby forms a closure for the air passage between said tubes and constrains the air therein to pass through the tubes and burn with the vapor in the combustion chambers 45 76 and 82.

The liquid fuel in the vaporizing channel is initially heated and vaporized by an electric heating element 90 which is in the form of a disc that is seated against the bottom face of the bottom 50 wall 30 of the vaporizing channel and imparts heat thereto. The heating element is provided with an annular opening 92 in the middle thereof which surrounds the open bottom ends of the 55 passages 38 so that air can flow freely into said passages through said opening. When said heating element is used for initially vaporizing the oil, the aforesaid wicks are unnecessary.

With the arrangement above described a single feed pipe suffices to distribute the fuel into the 60 annular vaporizing channel at a plurality of angularly spaced locations whereby to assure a uniform distribution of fuel in said channel and to avoid the starting of parts thereof. The fuel passages 48 are open at the top their entire length 65 so that they can be cleaned readily, by removing the cap 56 and its associated parts, if carbon deposits should form therein. The passages are relatively narrow and are surrounded by heat conducting walls so that when the burner is in

steady operation the liquid fuel is vaporized largely in said passages.

Ribs 94 are located between the ribs 52 and integrally connect the rings 12 and 14 for the purpose of providing additional thermal paths for the conduction of heat from the inner ring to the outer ring, so as to facilitate the transfer of the heat of the electric heating element to the outer ring, and the vaporization of the liquid oil that is present in the outer channel 24, at the time 85 of starting the cold burner in operation.

I claim:

1. A liquid fuel burner comprising a base having upstanding walls providing an outer narrow open top vapor channel and an inner wide open top vaporizing channel with an annular air passage between said channels, said base also having means providing a central fuel inlet surrounded by said wide inner channel and open top fuel ducts which extend from said inlet to said wide inner channel and air passages through said base between said fuel ducts, a removable cap seated on said base above said ducts and air passages and constituting a closure for the open tops of said ducts and itself having air passages which register with and form continuations of the air passages of said base, said cap having a rim that is extended over said wide channel and is terminated close to and is closely spaced from the outer wall of said wide channel to provide a 105 narrow annular opening therefor, outer and inner closely spaced combustion tubes carried respectively by said base and said rim and surrounding and upstanding above said opening, other outer and inner combustion tubes carried by said base 110 and surrounding and upstanding above the open top of said outer vapor channel, and fuel ducts providing communication between said outer and inner channels.

2. A liquid fuel burner comprising a base having upstanding walls providing an outer narrow open top vapor channel and an inner wide open top vaporizing channel with an annular air passage between said channels, said base also having means providing a central fuel inlet surrounded by said wide inner channel and open top fuel ducts which extend from said inlet to said wide inner channel and air passages through said base between said fuel ducts, a removable cap seated on said base above said ducts and air passages 120 and constituting a closure for the open tops of said ducts and itself having air passages which register with and form continuations of the air passages of said base, said cap having a rim that is extended over said wide inner channel and is terminated close to and is closely spaced from the outer wall of said wide channel to provide a 125 narrow annular opening therefor, outer and inner closely spaced combustion tubes carried respectively by said base and said rim and surrounding and upstanding above said narrow annular opening, and other outer and inner combustion tubes carried by said base and surrounding and upstanding above the open top of said outer channel, said base having vapor ducts which connect said 130 outer and inner channels and open into said inner channel between said fuel ducts.

WILLIAM EDWARD TAFT.
